CLAIM

The ornamental design for a toy, as shown and described.

DESCRIPTION

FIG. 1 is a perspective view of a toy showing our new design;

FIG. 2 is a top plan view thereof;

FIG. 3 is a left side elevational view thereof; and

FIG. 4 is a front elevational view thereof.

FIG. 5 is a perspective view of another embodiment of a toy showing our new design;

FIG. 6 is a top plan view thereof;

FIG. 7 is a right side elevational view thereof; and,

FIG. 8 is a front elevational view thereof.

Portions in broken lines are for illustrative purposes only and form no part of the claimed design.
